UNITED STATES PATENT OFFICE.

LEE C. FERGUSON, OF MARION, INDIANA, ASSIGNOR TO POSITIVE RAIL ANCHOR COMPANY, OF MARION, INDIANA, A CORPORATION.

RAIL-ANCHOR.

1,234,647.

Specification of Letters Patent. Patented July 24, 1917.

Application filed March 26, 1917. Serial No. 157,376.

To all whom it may concern:

Be it known that I, LEE C. FERGUSON, a citizen of the United States, residing at Marion, in the county of Grant and State of Indiana, have invented certain new and useful Improvements in Rail-Anchors, of which I do declare the following to be a full, clear, and exact description, reference being had to the accompanying drawing, forming part 10 of this specification.

The present invention has for its object to provide an improved construction of rail anchor, the improvements being directed more particularly to that type of rail anchor 15 in which a body member adapted to extend beneath the base of the rail is provided at its opposite ends with jaws to engage the base flanges of the rail and is provided at one end with an abutment adapted to bear against 20 the side of the cross tie of the track. In this type of rail anchors, it has been found that when the abutment that depends from one end of the rail anchor is embedded in the ballast and there is any tendency of the rail 25 to move (as in contracting and expanding) in a direction opposite that in which the rail tends to creep under the normal conditions of traffic, there is danger of the rail anchor becoming loosened and losing its grip upon 30 the base flanges of the rail.

My present invention has for its object to provide the rail anchor with a depending abutment of such construction that any tendency to move the anchor away from the cross 35 tie shall have the effect of tightening the bite of the rail gripping jaws upon the base flanges of the rail. This object I accomplish by forming the abutment with a wall that inclines or curves in a direction from the end 40 of the anchor toward its center. The construction and mode of operation of my improved anchor will be understood from the following description taken in connection with the accompanying drawing.

45 Figure 1 shows a plan view of a portion of a railroad rail with my improved anchor applied thereto, a part of a cross tie being also shown. Fig. 2 is a vertical section on line 2—2 of Fig. 1. Fig. 3 is a view in side 50 elevation.

A designates the body portion of my improved anchor that is adapted to extend beneath the base of the railroad rail B, this body portion A being provided at its opposite ends with the rail gripping jaws a and

a' adapted to engage respectively the base flanges b and b' of the rail B.

At one end the body member A is provided with an offset, depending abutment C adapted to bear against the side of the cross 60 tie D. Except as to the shape of the abutment C, the rail anchor above described is of the familiar type commonly known as the "positive" rail anchor. This type of rail anchor is usually formed as a single casting 65 with integral jaws at its opposite ends, the construction of the anchor being such that as the rail tends to creep in the direction of the large arrow, Fig. 1, the movement is resisted by the engagement of the abutment 70 at one end with the cross tie, while the opposite or free end of the anchor moves slightly farther toward the cross tie. The result is that the anchor turns slightly on the abutment as a pivot and the rail gripping jaws 75 of the anchor are caused to more tightly grip the corresponding base flanges of the rail.

The abutment C is shown as comprising a depending flange or web the front end of 80 which is adapted to contact with the cross tie D, while the rear portion of this flange or web tapers upwardly toward the end of the body portion A with which the web or flange is integrally cast. The rear face or 85 wall of the abutment C is inclined inwardly from the end of the body portion A toward the cross tie D, as indicated by the dotted line c in Fig. 1 of the drawing, and preferably the outer face c' of the abutment C is 90 correspondingly inclined or curved. My purpose in forming the abutment with its rear wall c inclined inwardly toward the cross tie is to insure that when there is any movement of the anchor away from the tie 95 D,—as sometimes occurs with the contraction of the rail B,—the movement of the inclined depending wall of the abutment through the ballast will cause the rail gripping jaw a at the opposite end of the anchor to more firmly bind upon the flange b of the rail. That is to say, as the abutment C (embedded in the ballast) is moved away from the tie D, the forcing of the inclined wall c of the abutment through the ballast 100 tends to shift the anchor laterally and at the same time swing it slightly, thereby causing the jaw a at the opposite end of the anchor to more firmly engage the flange b of the rail and at the same time causing the jaw a' 110

to maintain its grip upon the rail flange b' . In prior constructions of rail anchors of this type, the depending walls of the abutments have been substantially parallel with the cross tie D, with the result that when the rail B contracted and thus tended to move the anchor A away from the cross tie D, the abutment embedded in the ballast tended merely to hold the adjacent end of the anchor while allowing the rail gripping jaw a at the opposite free end of the anchor to move slightly away from the tie and in so doing to release the grip of the jaws a and a' upon the rail flanges. When the abutment, however, has its rear wall inclined inwardly toward the cross tie, as in my present invention, such danger of the loosening of the anchor is avoided.

While I have shown what I regard as the preferred form of the invention, it is obvious that the precise shape of the abutment may be modified so long as said abutment is so shaped that as the anchor is moved away from the cross tie it shall exert a thrust

tending to tighten the grip of the anchor 25 upon the rail.

Having thus described my invention, what I claim as new and desire to secure by Letters Patent is:—

1. A rail anchor adapted to extend beneath the base of the rail and having at its opposite ends jaws to grip the base flanges of the rail, and an abutment to engage one of the cross ties of the rail, said abutment being shaped to impart a lateral movement 30 to the anchor as it is moved away from the cross tie and through the ballast.

2. A rail anchor adapted to extend beneath the base of the rail and provided at its opposite ends with means to grip the base flanges of the rail and with a downwardly extending abutment to engage one of the cross ties of the rail, said abutment having 40 its rear wall so inclined inwardly toward said cross tie as to impart a lateral thrust 45 to the anchor as it is moved away from the cross tie and through the ballast.

LEE C. FERGUSON.
